UNITED STATES PATENT OFFICE.

WILLIAM S. LEMPERT, OF MARFA, TEXAS.

DEVICE FOR RAISING WATER.

SPECIFICATION forming part of Letters Patent No. 599,658, dated February 22, 1898.

Application filed February 9, 1897. Serial No. 622,609. (No model.)

To all whom it may concern:

Be it known that I, WILLIAM S. LEMPERT, of Marfa, in the county of Presidio and State of Texas, have invented a new and Improved 5 Device for Raising Water, of which the following is a full, clear, and exact description.

The object of the invention is to provide a new and improved device for raising water by use of a compressed fluid, such as air, the 10 device being arranged to insure a continuous flow of water.

The invention consists of certain parts and details and combinations of the same, as will be fully described hereinafter and then pointed out in the claims.

Reference is to be had to the accompanying drawings, forming a part of this specification, in which similar characters of reference indicate corresponding parts in all the figures.

Figure 1 is a sectional side elevation of the improvement on the line 1 1 of Fig. 2 and showing a box with several compartments.

Fig. 2 is a sectional plan view of the same on the line 2 2 of Fig. 1. Fig. 3 is a transverse

25 section of the air-chest. Fig. 4 is a sectional side elevation of the same; and Fig. 5 is a sectional side elevation of the improvement, showing a box with a single compartment and connected with a locomotive.

30 As shown in Figs. 1 and 2, the well A contains a box B, completely submerged in the well-water and formed with a partition B', so as to produce the compartments B² B³ in the box B. The compartments are provided with

35 water-inlet valves C and C' and respectively adapted to swing inward and open when the pressure of the water outside the box is greater than that exerted within the compartment, so that the water from the well fills the corresponding compartment.

40 Into the top of each compartment opens an air-supply pipe D or D', provided with valves D² D³, respectively, and connected with an air-chest E, arranged on an air-pipe F, connected with an air-compressor or other suitable device for forcing air through the said pipe F to the chest E. The latter is provided

45 with a valve mechanism having valves E' and E² for permitting the compressed air to flow alternately to the pipes D and D', so that the air passes into the corresponding com-

partment B² or B³ to press on the water contained in the filled compartment.

The valves E' and E² operate over ports a and b, respectively, connecting the chest E 55 with the pipes D D', respectively, and the said valves are secured on a valve-stem E³, adapted to be turned by the operator or by an automatic device set according to the time required for filling and emptying the compartments B² and B³ in the tank B. On the valve-stem E³ are secured vent-valves E⁴ E⁵, operating over ports c and d for connecting the ports a and b and the pipes D and D', respectively, with vent-pipes E⁶ and E⁷, leading 60 to the atmosphere. All the valves E', E², E⁴, and E⁵ operate in unison and are so arranged that when the valves E' and E⁵ are open the valves E² and E⁴ are closed, and vice versa. The chest E is also provided with an 65 air-outlet pipe F', normally closed by a suitable safety-valve F², adapted to open on an excess of pressure in the chest.

The compartments B² and B³ are provided with water-outlet pipes G and G', extending 75 with their lower open ends within a short distance of the bottoms of the compartments, the said pipes being provided outside of the box B with check-valves H and H', respectively, as indicated in dotted lines in Fig. 1. 80 The pipes G and G' are connected above the check-valves with a common discharge-pipe G², extending out of the well to a suitable place of discharge, as indicated in Fig. 1. It is evident that the air-pressure in a filled compartment forces the water through the corresponding pipe G or G' to the outlet-pipe G², 85 so that the water is raised and discharged.

When a compartment is nearly empty, the valve mechanism in the air-chest E closes the 90 supply for the corresponding pipe D or D' and connects with the other pipe D' or D, so that the air now passes to the other compartment, which filled with water during the time the first compartment was emptying. The first 95 compartment is now relieved of its air-pressure by the vent-pipe connecting with the air-supply pipe D or D', so that water can pass through the corresponding valves C or C' into the compartment to again fill it from the well 100 A. Thus while one compartment is filling the other is discharging its water, the arrange-

ment for turning on and off the air being automatic and each pipe D or D' serving as an air-escape to permit the compartment to fill with water when the supply of air is shut off 5 from the corresponding pipe.

As illustrated in Fig. 5, the box B⁴ has but a single compartment and a valve C² submerged in the water contained in the well A' and self-closing, the same as the valves C C' 10 previously mentioned, the valve C² opening inward by the pressure of the water in the well whenever the pressure inside of the box in the well is removed, so that the box is filled with water from the well.

15 Into the top of the box B⁴ opens an air-inlet pipe D⁴, adapted to be connected by a hose I with the air pump or reservoir of a locomotive or other machine or device to permit of forcing air under pressure into the said box 20 B⁴ to press on the water therein to close the valve C² and to force the water out through a water-discharge or stand pipe G³, extending to within a short distance of the bottom of the box B⁴, the same as the pipes G and G' 25 previously mentioned. The upper end of the pipe G³ is connected by a hose J with the water-tank of the locomotive, so that by the use of the train air-pressure water can be forced out of the box to fill the locomotive-tank. 30 The pipe G³ is preferably provided in its lower portion with a check-valve G⁴ to prevent a return flow of the water in the upper part of the said pipe G³. It is evident that the device can be used for various other purposes besides 35 the one mentioned and shown in Fig. 5.

Having thus described my invention, I claim as new and desire to secure by Letters Patent—

1. A device for raising liquids, comprising 40 a box having compartments, inlet-valves for the said compartments to permit water to flow into the compartments, water-discharge pipes leading from the compartments and having check-valves, air-supply pipes open- 45 ing into the upper ends of the said compartments and provided with valves and an air-chest provided with a chamber connected with a source of supply of compressed air, the said air-chest being also provided with 50 chambers connected respectively with the said supply-pipes, and a valve mechanism for the said chest, consisting of a valve-stem mounted to turn in the said chest, valves carried by the said stem and arranged within 55 the chamber connected with the source of supply of compressed air, the said valves operating over ports leading to the chambers connected with the air-supply pipes to permit the compressed air to flow alternately to the said 60 air-supply pipes, and air-vent valves also carried by the said valve-stem and located within the chambers connected with the air-supply pipes, the said air-vent valves operating over

ports connecting the said chambers with air-vent pipes and allowing the air to escape from 65 the said air-supply pipes alternately, substantially as shown and described.

2. A device for raising liquids, comprising a box having separate compartments and arranged for submersion in water, the said box 70 having water-inlet valves for the said compartments, a water-outlet pipe for each compartment, an air-supply pipe for each compartment provided with a valve, an air-chest having a central chamber connected with a 75 source of supply of compressed air and end chambers connected respectively with the said air-supply pipes, the said air-chest being provided with ports connecting the central chamber with the end chambers and also 80 provided with vent-ports leading from the end chambers, a valve-stem mounted to turn in the said chest and carrying valves located in the said central chamber and operating over the ports leading to the end chambers 85 to permit the compressed air to flow alternately to the said end chambers and the air-supply pipes leading therefrom, the said valve-stem also carrying air-vent valves located in the end chambers of the said air-chest 90 and operating over ports leading from the said end chambers to allow the air to escape from said air-supply pipes alternately, and an air-outlet pipe connected with the central chamber of the said air-chest and normally 95 closed by a safety-valve, substantially as shown and described.

3. A device for raising liquids, comprising a closed box adapted to be submerged in water and having one or a plurality of water- 100 inlet valves, a water-discharge pipe leading from the said box, an air-supply pipe opening into the top of said box, an air-chest provided with a chamber connected with a source of supply of compressed air, the said 105 chamber having an air-outlet pipe normally closed by a safety-valve, the said air-chest being further provided with a second chamber connected with the said air-supply pipe, the said air-chest being provided with a port 110 connecting the two chambers and also provided with a vent-port leading from the said second chamber and a valve-stem mounted to turn in the said chest and provided with a valve located within the first-mentioned 115 chamber, the said valve operating over the port leading to the said second chamber, and an air-vent valve also carried by the said valve-stem and located within the second chamber and operating over the vent-port 120 leading from said chamber, substantially as shown and described.
